LOCOMOTIVE STOKER

Russell A. Mickle and Joseph B. MacKenzie, Erie,
Pa., assignors to The Standard Stoker Company,
Incorporated, a corporation of Delaware

Application October 22, 1938, Serial No. 236,444

13 Claims. (Cl. 110—105.5)

This invention relates to stokers of the type that communicate with the firebox through a firing opening in a wall thereof above the level of the firebox grate. More particularly the invention pertains to that portion of a stoker of the type described adjacent the firebox.

Referring particularly to a locomotive, for purpose of illustration, there are variations in the firebox dimensions, the inclination of the backhead, the height of the deck and other differences in construction giving rise to numerous problems and difficulties in the application of stokers thereto. To provide a particular design of stoker discharge casing and distributing mechanism for each different locomotive construction would among other things necessitate the use of an excessive number of large and expensive patterns, maintenance of an inventory of a great many parts and render interchangeability of parts impossible. It is, therefore, one object of the invention to provide a stoker of standard design that can be readily applied to furnaces of different design and construction, and particularly to provide a stoker for application to various types of locomotive fireboxes.

It is another object of the invention to provide for adjustment of certain parts of the distributing mechanism of a stoker to compensate for variable firebox constructions and for fuel of different characteristics.

In stokers of the type feeding to an opening in an upright wall of the firebox, it is customary to provide a distributing mechanism across which fuel passes from the stoker conduit to the firebox and longitudinally extending upstanding vanes or deflectors for deflecting or guiding the fuel as it passes across the distributing mechanism. It is another object of the invention to provide in such constructions a distributing mechanism that is capable of adjustment to various positions independently of the fuel deflectors and means forming a seal between the deflectors and the distributing mechanism in any of the adjusted positions of the latter.

The invention accordingly consists in the various details of construction, combination of elements, and arrangement of parts as will appear from the following description when read in connection with the accompanying drawings, in which—

Fig. 1 is a central, vertical, longitudinal section through a portion of a locomotive and its firebox with the novel stoker and distributing mechanism applied thereto and shown in side elevation;

Fig. 2 is a fragmentary sectional view taken on the line 2—2 of Fig. 1;

Fig. 3 is a fragmentary central, vertical, longitudinal sectional view of a firebox and stoker with the novel distributing mechanism in position and shown in similar section;

Fig. 4 is an enlarged fragmentary section view of a portion of the construction illustrated in Fig. 3, showing the connection between the adjacent ends of the stoker conduit and distributing mechanism;

Fig. 5 is a fragmentary sectional view of one of the deflectors and sealing means taken on the line 5—5 of Fig. 6, the distributor head being shown in elevation; and

Fig. 6 is a fragmentary longitudinal, vertical, sectional view of the stoker discharge conduit with the deflecting, distributing and sealing means applied thereto and shown in section taken on the line 6—6 of Fig. 5.

The invention has been shown in the drawings as applied to a locomotive firebox and will be so described, however, it will become apparent as the description proceeds that the invention is equally applicable to other types of fireboxes.

Referring to the drawings, a locomotive, indicated generally by the letter A, includes a boiler firebox 10 having a backwall 11 provided with a firing opening 12 above the level of the locomotive cab deck 13.

Fuel is delivered to the firebox 10 from a suitable source of supply, as from a tender fuel bin (not shown), by a stoker S which communicates at its discharge end with the lower portion of the firing opening 12. The upper portion of the firing opening is provided with a firedoor 14 arranged for manual or power operation. The stoker S includes a conduit 15 extending upwardly and forwardly from beneath the cab deck to the firing opening and may be secured at its upper forward end to the backwall 11 by angle bars 16 or other suitable means. Fuel is conveyed forwardly and upwardly toward the firing opening 12 by a conveyor screw 17 disposed within the conduit 15. At its lower end, the conduit 15 is connected with a conduit 18 leading forwardly from the source of fuel supply, and a ball and socket joint 19 provides for the necessary flexibility between the conduits during operation of the locomotive.

Depending from the sides of the conduit 15 near the lower end thereof are feet 20 and 21 provided, respectively, with downwardly opening forked end portions 22 and 23. A bracket 24 is rigidly secured to the backhead 11 and is pro-

vided with upstanding laterally spaced ears 25 and 26 arranged to be received in the forked portions 22 and 23, respectively, of the feet 20 and 21, respectively. Bolts 27 and 28 passing loosely through the forked end portions 22 and 23, respectively; and the ears 25 and 26, respectively, form a pivotal support for the conduit 15 permitting fore and aft movement of the conduit 15 about the bolts 27 and 28 as an axis. The holes in the ears 25 and 26 can be made at the time the stoker is installed in the locomotive to bring them in register with the holes in the forked end portions 22 and 23 of the feet 20 and 21.

15 Fuel is conveyed by the conveyor screw 17 to a distributing mechanism which will now be described in detail. The distributing mechanism includes a pressure fluid jet head 29 disposed in the lower portion of the firing opening 12 at the discharge end of the conduit 15. The jet head 29 comprises a plurality of walls defining there-in the chambers 30 and 31, including a flat top wall 32 across which the fuel is urged from the conduit 15 by the conveyor screw 17, and a front wall 33 provided with a plurality of jet openings 34 communicating with the chambers 30 and 31. The fuel passing across the top wall 32 of the jet head drops in front of the front wall 33 onto a distributing table 35 which is detachably secured to and supported from the jet head 29 in the following manner. The rear edge portion of the top wall 36 of the table 35 rests on a ledge 37 that extends forwardly from the lower forward edge of the jet head 29. Depending from the underside of the table top wall 36 are rearwardly extending lugs 38 provided with the up-standing curved ribs 39 which cooperate with a complementary curved wall 40 of the jet head 29 to hingedly connect the jet head 29 and the distributing table 35.

40 In order to provide for cooling of the distributing table 35, it is provided with a depending apron 41 defining a chamber 45 open at its rearward end, through which opening a current of air is drawn from outside the firebox. A plurality of perforations 46 are provided in the apron 41 of the distributing table 35 through which the air is drawn from the chamber 45 into the firebox. A sealing member 47 is mounted in 45 the chamber 45 on the bottom wall of the apron 41, and forms a closure for the gap between the rearward edge of the apron and the inside sheet of the backhead.

45 The jet head 29 is hingedly supported by the conduit 15 for adjustment about a transverse horizontally extending axis whereby the jet head 29 and distributing table may be made to assume the same relative position in the firing opening irrespective of the slope of the stoker conduit 15 or may be adjusted to a position best adapted for distributing fuel over the firebed in the firebox. Fluid under pressure is supplied to the chambers 30 and 31 from a suitable source of supply through openings 48 in the rearwardly extending cored portion 49 of the jet head 29 and issues from the jet openings 34 for projecting the fuel from the distributing table 35.

50 To provide for the hinging movement of the jet head 29, the forward edge of the bottom wall 50 of the conduit 15 is formed with a transversely extending arcuate indentation 51 arranged to receive the rolled edge 52 at the rearward end of the top wall 32 of the jet head 29. In order to secure the jet head 29 in adjusted position, its 55 rearward extension 49 is provided with a lug

53 having an opening 54 which registers with an arcuate slot 55 in a lug 56 projecting outwardly from the conduit 15. A bolt 57 threaded at one end passes through the opening 54 and slot 55 and a lock nut 58 is threaded on the threaded portion of the bolt 57, which when drawn up tightly will secure the jet head 29 in place.

58 As a control for distribution of fuel, deflector vanes 59 and 60 are provided, one at each side of the delivery end of the stoker conduit. Each 10 vane is pivotally mounted at its rearward end on an upstanding axis for movement over the top wall 32 of the jet head 29 whereby more or less fuel may be delivered onto one side or the other of the top wall 36 of the table 35. To maintain 15 a seal between the lower edge of the vanes 59 and 60 and the top wall 32 of the jet head 29 irrespective of the inclination of the top wall 32 of the jet head 29, a novel construction and arrangement of elements is provided. This construction and arrangement is shown in Figs. 5 and 6 relative to the vane 60 and will be so described, it will be understood, however, that the same construction and relation of elements applies to the vane 59.

25 The vane 60 is provided near its lower edge with an outwardly and downwardly extending flange 61 forming with the lower portion of the vane 60 a downwardly opening recess 62. A longitudinally extending plate 63 is received loosely in the recess 62 and rests on the top wall 32 of the jet head 29. A spring 64 disposed in the recess 62 between the flange 61 and the upper end of the plate 63 forces the plate 63 downwardly in contact with the top wall 32 of the jet head 29, thus maintaining a seal between the lower edge of the vane 60 and the top wall of the jet head irrespective of the relative positions of the conduit 15 and the jet head 29.

30 Elongated slots 65 are preferably provided in 40 the plate 63 and pins 66 passing through the flange 61, vane 60 and slots 65 prevents fore and aft movement of the plate 63.

35 It is apparent, therefore, that the inclination of the conduit 15 may be varied to a considerable extent to suit the particular firebox or locomotive construction, while maintaining a desired position of the distributing mechanism in the firing opening and maintaining a seal against leakage of the coal between the deflector vanes 50 and the distributing mechanism.

40 We claim:

1. The combination in a stoker of a fuel distributor, fuel deflecting means disposed above and spaced from said distributor and a plate-like member engaging said deflecting means, said plate-like member being arranged for relative upward and downward movement with respect to said deflecting means and the lower edge thereof resting on said distributor, said plate-like member forming a seal between the distributor and the deflecting means.

45 2. The combination in a stoker of a fuel distributor, fuel deflecting means above said distributor, said distributor and deflecting means 65 being arranged for relative movement in an upward and downward direction, and a plate-like member engaging said deflecting means, said plate-like member being arranged for relative upward and downward movement with respect 50 to said deflecting means to form a seal between the distributor and the deflecting means in any one of their relative positions.

55 3. The combination in a stoker of a fuel distributor, fuel deflecting means above said distributor, fuel deflecting means above said dis-

tributor, said distributor and deflecting means being arranged for relative movement in an upward and downward direction, a plate-like member engaging said deflecting means, said plate-like member being arranged for relative upward and downward movement with respect to said deflecting means to form a seal between the distributor and the deflecting means in any one of their relative positions, and yieldable means for maintaining said plate-like member in contact with said distributor.

4. The combination in a stoker of a fuel distributor, a fuel deflecting vane above said distributor, said distributor and deflecting vane being arranged for relative movement in an upward and downward direction, said deflecting vane being provided in its lower end with a downwardly opening channel extending longitudinally of the vane, a plate-like member in said channel, said plate-like member being arranged for relative upward and downward movement with respect to said deflecting vane to form a seal between the distributor and the deflecting vane in any one of their relative positions, and yieldable means for maintaining said plate-like member in contact with said distributor.

5. The combination in a stoker of a fuel distributor having a flat top surface, a pair of laterally spaced longitudinally extending deflecting vanes above said distributor, said distributor and deflecting vanes being arranged for relative movement in an upward and downward direction, a plate-like member engaging each of said vanes and extending in the direction of said vanes, said plate-like members being arranged for relative upward and downward movement with respect to said vanes to form seals between the distributor and the deflecting vanes in any one of their relative positions, and yieldable means for maintaining said plate-like members in contact with the flat top surface of said distributor.

6. The combination in a stoker of a fuel distributor having a flat top surface, a pair of laterally spaced longitudinally extending deflecting vanes above said distributor, said distributor and deflecting vanes being arranged for relative movement in an upward and downward direction, each of said deflecting vanes being provided in its lower end with a downwardly opening channel extending longitudinally of the vane, a plate-like member in each of said channels extending in the direction of said respective vane, said plate-like members being arranged for relative upward and downward movement with respect to said vanes to form seals between the distributor and the deflecting vanes in any one of their relative positions, and yieldable means for maintaining said plate-like members in contact with the flat top surface of said distributor.

7. In combination with a stoker discharge conduit, a fuel distributor arranged to receive fuel from said discharge conduit, deflecting means above said distributor adapted to act on the fuel, said distributor being mounted with the bottom wall of said discharge conduit at the discharge end thereof for pivotal movement about a transverse axis toward and away from the deflecting means and means associated with said deflecting means forming a seal between the distributor and the deflecting means in any one of a number of positions of said distributor.

8. In combination with a stoker discharge conduit, a fuel distributor arranged to receive fuel from said discharge conduit, deflecting means

above said distributor adapted to act on the fuel, said distributor being mounted with the bottom wall of said discharge conduit at the discharge end thereof for pivotal movement about a transverse axis toward and away from the deflecting means and a plate-like member engaging said deflecting means, said plate-like member being arranged for relative upward and downward movement with respect to said deflecting means to form a seal between the distributor and the deflecting means in any one of a number of positions of said distributor.

9. In combination with a stoker discharge conduit, a fuel distributor arranged to receive fuel from said discharge conduit, deflecting means above said distributor adapted to act on the fuel, said distributor being mounted with the bottom wall of said discharge conduit at the discharge end thereof for pivotal movement about a transverse axis toward and away from the deflecting means, a plate-like member engaging said deflecting means, said plate-like member being arranged for relative upward and downward movement with respect to said deflecting means to form a seal between the distributor and the deflecting means in any one of a number of positions of said distributor.

10. In combination with a stoker discharge conduit, a fuel distributor arranged to receive fuel from said discharge conduit, deflecting means above said distributor mounted with said conduit for movement about an upwardly extending axis, said distributor being mounted with the bottom wall of said discharge conduit at the discharge end thereof for pivotal movement about a transverse axis toward and away from the deflecting means and means associated with said deflecting means forming a seal between the distributor and the deflecting means in any one of a number of positions of said distributor.

11. In combination with a stoker discharge conduit, a fuel distributor arranged to receive fuel from said discharge conduit, deflecting means above said distributor mounted with said conduit for movement about an upwardly extending axis, said distributor being mounted with the bottom wall of said discharge conduit at the discharge end thereof for pivotal movement about a transverse axis toward and away from the deflecting means and a plate-like member engaging said deflecting means, said plate-like member being arranged for relative upward and downward movement with respect to said deflecting means to form a seal between the distributor and the deflecting means in any one of a number of positions of said distributor.

12. In a furnace having an upstanding wall with a firing opening therein, a fuel discharge conduit communicating with said firing opening, a pressure fluid jet head at the forward end of said discharge conduit, said pressure fluid jet head being mounted with respect to said discharge conduit for pivotal movement about a transversely extending axis, means providing a plurality of chambers in said jet head forward of the pivotal connection between said conduit and said jet head, said jet head having a cored portion extending rearwardly beneath said discharge conduit and rearwardly of the pivotal connection between said conduit and said jet head, the cored portion of said jet head arranged to receive fluid under pressure for delivery to said chambers, and means at the terminal end of the cored portion

of said jet head for securing the latter in any one of a number of positions of adjustment about the transversely extending axis.

13. In a furnace having an upstanding wall 5 with a firing opening therein, a fuel discharge conduit member communicating with said firing opening, a pressure fluid receiving member extending forwardly from the forward edge of the bottom wall of the said discharge conduit member, one of the adjacent ends of said members having a transversely extending rolled edge and the other of said adjacent ends having a complementary grooved surface receiving said rolled edge to provide a pivotal connection whereby one 10 member may move with respect to the other mem- 15

ber about a transversely extending axis, means providing a plurality of chambers in said pressure fluid receiving member forward of the pivotal connection between said members, said pressure fluid receiving member having a cored portion extended rearwardly beneath said discharge conduit and rearwardly of the pivotal connection between said members, and means at the terminal end of the cored portion of said pressure fluid receiving member for securing the latter in any 10 one of the number of positions of adjustment about the transversely extending axis. 5
